UNITED STATES PATENT OFFICE.

MELWOOD B. AYRES, OF MELROSE PARK, AND CHARLES S. MORRISON, OF ELKINS PARK, PENNSYLVANIA, ASSIGNORS TO PROCTOR & SCHWARTZ, INCORPORATED, OF PHILADELPHIA, PENNSYLVANIA, A CORPORATION OF PENNSYLVANIA.

TOGGLE.

Application filed April 22, 1925. Serial No. 25,104.

Our invention relates to certain improvements in toggles, used in stretching leather on frames during the process of manufacture. The invention is an improvement on that disclosed in an application for patent filed May 27, 1924, under Serial No. 716,134.

The object of the present invention is to improve the construction of a toggle so that it will grip the leather firmly and will hold the leather positively during the drying process.

The invention also relates to certain details of construction, which will be described hereinafter.

In the accompanying drawings:

Fig. 1 is a perspective view of our improved toggle;

Fig. 2 is a side view, showing the toggle in the open position;

Fig. 3 is a sectional view, showing the toggle in the closed, or gripping, position;

Fig. 4 is a front view;

Fig. 5 is a rear view;

Fig. 6 is an inverted plan view;

Fig. 7 is a detached perspective view of the eccentric jaw;

Fig. 8 is a detached perspective view of the U-shaped bearing and two plates; and

Fig. 9 is a detached perspective view of the hook.

The body 1 of the toggle is made of metal, bent to form a finger hold 2, and also forms the carrier for the pivoted jaw 3. The body of the toggle is bent at each side to form flanges 4, between which is located the eccentric toothed jaw 5. The eccentric jaw 5 has trunnions 6, which extend through holes in the side flanges 4. At the rear of the eccentric jaw 5 is a stop 7, which strikes the body 1 when the jaw is turned to its extreme position, shown in Fig. 2.

The main jaw has flanges 8 at each side and has a rounded outlet end. The flanges are perforated for the pivot projections 9, formed of the portion 2 of the body. A brace 10 extends across the toggle and connects the body with the curved end of the finger hold, as shown in Fig. 3. A U-shaped bearing 11 extends through two slots in the body 1 and through slots in the main jaw 3. Pivoted to the bearing 11 is a lever 12. On the short arm of the lever is a roller 13, which bears upon a plate 14 mounted on the jaw 3 between its flanges. This plate

is notched to allow clearance for the ends 65 of the bearing 11 and has a stop 15 for the roller 13.

Arranged to slide on the bearing 11, back of the jaw 3, is a flanged plate 16, Fig. 8. A spring is located between the plate 16 and the body 1. A centering stud 17 on the body extends in the spring.

The body 1 is recessed at the back to receive a hooked plate 18. The plate is bent to receive the bearing 11 so that the plate 65 is held in place on the body of the toggle. The hooked end 19 of the plate is arranged to engage a support 20 of any suitable type, as illustrated in Fig. 3.

By the construction, hereinbefore described, the hooked plate can be readily removed and replaced when desired.

The support 20, which may be a wire netting, or a perforated plate, is carried by a suitable frame.

The leather is placed in position on the support and the toggles are applied to the edges of the leather. The toggles are pulled to stretch the leather, and, while the leather is under tension, the toggles are hooked onto 75 the support, the leather being held away from the surface of the support by the toggles.

The main jaw and the eccentric jaw are made of brass, or bronze, to avoid staining 85 the leather, and the hooked plate is made detachable. The eccentric jaw has teeth, which are so designed that they engage the leather positively on moving the hand lever, when the leather is clamped. 90

This construction of toggles makes it unnecessary to temper the steel parts.

We claim:

1. The combination in a toggle, of a body portion bent to form a finger hold; a jaw 95 pivoted to the body; a main jaw pivoted to the end of that portion forming the finger hold; a bearing extending from the body through the main jaw; and a lever, on the bearing, engaging the main jaw.

2. The combination in a toggle, of a body portion bent to form a finger hold; a movable main jaw pivoted to the outer end of the finger hold; an eccentric jaw pivoted to the body opposite the main jaw; and means 105 for moving the main jaw towards the eccentric jaw.

3. The combination in a toggle, of a body

portion having a finger hold at one end; a brace; a main jaw pivoted to the finger hold; a U-shaped bearing extending from the back of the body portion and through the main jaw; a hand lever pivoted to the bearing and having a roller; a plate on the main jaw, against which the roller rests; a stop on the plate for the roller; a detachable hooked plate at the back of the body portion; and 10 an eccentric jaw pivoted to the body portion and having teeth, said eccentric jaw being opposite the main jaw.

4. The combination in a toggle, of a body portion having an extension in the form of a hand-hold; a main jaw pivoted to the extension; a hooked plate detachably secured to the back of the body portion; a bearing extending through the body portion and main jaw; a second jaw mounted on the body portion opposite the main jaw; and an operating lever mounted on the bearing for actuating the main jaw, the bearing retaining the hooked plate in position on the body portion.

5. The combination in a toggle, of a body

portion having an extension recessed at the back and slotted; a U-shaped bearing extending through the slots of the body portion; a hooked plate mounted in the recess of the body portion and recessed to receive the bearing; a main jaw carried by the extension of the body portion; a second jaw mounted on the body portion opposite the main jaw; and mechanism for actuating the main jaw, said mechanism being mounted on the bearing.

6. The combination in a toggle, of a body portion having an extension at one end forming a hand-hold, said body portion being flanged at each side; an eccentric toothed jaw pivoted to the flanges; a main jaw located opposite the eccentric toothed jaw; and having a flange at each side, said flanges of the main jaw being pivoted to the extension of the body portion; a bearing extending from the body portion through the main jaw; and a lever mounted on the bearing and acting upon the main jaw.
